UNITED STATES PATENT OFFICE.

LOUIS E. CHASE, OF WILKINSONVILLE, MASSACHUSETTS.

LOOM-SHUTTLE.

1,248,077.

Specification of Letters Patent.

Patented Nov. 27, 1917.

Application filed April 2, 1917. Serial No. 159,056.

To all whom it may concern:

Be it known that I, LOUIS E. CHASE, a citizen of the United States, residing at Wilkinsonville, in the county of Worcester and 5 State of Massachusetts, have invented a new and useful Loom-Shuttle, of which the following is a specification.

This invention relates to a loom shuttle and particularly to certain improvements in 10 the devices for holding a weft carrier therein.

Such devices for use in automatic weft replenishing looms commonly comprise a pair of weft carrier holding jaws, means to hold said jaws securely in the shuttle, and a guide 15 plate by which the incoming weft carrier is directed to its proper position.

It is the object of my invention to provide a construction in which the several parts above mentioned will be more firmly supported in the shuttle, and in which accidental relative displacement of the parts is effectively prevented.

With this general object in view my invention comprises certain arrangements and 25 combinations of parts by which simplicity of construction and economy of manufacture are secured. These arrangements and combinations will be hereinafter described and more particularly pointed out in the appended 30 claims.

A preferred form of my invention and two modifications thereof are shown in the drawings, in which—

Figure 1 is a plan view of a portion of a 35 shuttle having my improved weft carrier holding devices embodied therein;

Fig. 2 is a vertical longitudinal sectional view taken along the line 2—2 in Fig. 1;

Fig. 3 is a transverse sectional view taken 40 along the line 3—3 in Fig. 2;

Fig. 4 is a plan view of the weft carrier holding jaws and the shank piece to which they are secured;

Fig. 5 is a side elevation of the parts 45 shown in Fig. 4;

Fig. 6 is a perspective view of a filler piece to be described;

Fig. 7 is a detail transverse sectional elevation taken along the line 7—7 in Fig. 1;

Fig. 8 is a partial perspective view of a 50 modification, and

Fig. 9 is a partial side elevation of a second modification.

Referring to the drawings, I have shown 55 a portion of a shuttle 10 of a common type, said shuttle having a central opening ex-

tending entirely through the shuttle from top to bottom as is usual in shuttles intended for use in automatic weft replenishing looms.

My improved weft carrier holding device 60 consists primarily of a pair of spring jaws 11 and 12 grooved at 13 to receive the butt rings of a weft carrier or bobbin 14 (Fig. 1). The jaws 11 and 12 are welded to an intermediate or shank piece 15 having a projection 16 extending above the jaws 11 and 12. In the form shown in Figs. 1 to 7 the projection 16 is cut away at its outer end to form a shoulder 17 (Fig. 5). The shank piece is preferably formed of relatively 70 soft, untempered material such as mild steel or wrought iron.

A guide plate of the usual form is used, comprising a base portion 20, an inclined directing portion 21 and an upper portion 22. 75 The jaws 11 and 12 and shank 15 rest upon the base portion 20, and the upper portion 22 is firmly engaged and supported by the projection 16 of the shank piece 15. The guide plate is secured in the shuttle by the 80 usual screw 23, and the spring jaws are also secured in place by a pin 24 shown in section in Fig. 2.

In the preferred form I also provide a U-shaped filler member 25 (Fig. 6) adapted to 85 inclose the projection 16 and provided at its open end with beveled parts 25a adapted to engage and support the inclined directing portion 21 of the guide plate. Reference to Fig. 7 will show that the filler piece 25 fits 90 closely between the projection 16 of the shank piece 15 and the side walls of the shuttle 10, thus providing additional lateral bearing surface on the wood of the shuttle without increasing the width of the expensive stock used to form the spring jaws 11 and 12. The filler 25 also rests upon the top edges of the springs 11 and 12 and engages the under side of the portion 22 of the guide plate, thus providing an additional bearing surface for said plate. Furthermore, the left-hand or closed end of the filler (as viewed in Fig. 2) engages the end wall of the recess in the shuttle, while the beveled parts upon the right-hand end engage and support the directing portion 12 of the guide plate, and also serve to definitely position the guide plate longitudinally in the shuttle.

It is found that this construction possesses many important advantages. The formation of the weft carrier holding

springs as separate spring members welded to a soft shank piece is found in practice to produce an extremely serviceable pair of spring jaws, and the breakage heretofore 5 common in these holding jaws is largely reduced. The provision of the upward projection 16 firmly supporting the upper portion 22 of the guide plate adds much to the 10 rigidity of the structure and this is still further increased by the use of the curved 15 filler piece 25.

While the construction above described is a preferred construction, many of the advantages of my invention may be retained 15 when the filler piece 25 is omitted, while at the same time the cost of construction is correspondingly reduced. When the filler 20 piece is omitted I prefer to form the shank piece as shown in Fig. 8, the projection 16^a being of the full size of the shank piece, while the cut-out shoulder 17 is omitted. This 25 projection serves the same functions as the preferred form of shank piece, but does not permit the use of the filler piece previously described.

In Fig. 9 I have shown a second modification in which the shank piece is prolonged to directly engage the inclined directing portion of the guide plate. This 30 form is the strongest and most rigid of the forms described herein but is also slightly more expensive to manufacture.

Having thus described my invention, it will be evident that other changes and 35 modifications can be made therein by those skilled in the art without departing from the spirit and scope of my invention as set forth in the claims, and I do not wish to be otherwise limited to the details herein disclosed, but what I claim is:—

1. In a loom shuttle, a pair of weft carrier holding spring jaws each formed from a separate strip of spring steel, a shank of soft steel to which one end of each jaw is 45 welded, said shank and jaws forming a single integral structure, said shank having a projection extending above the plane of said jaws, a guide plate secured in said shuttle and having a lower portion supporting said 50 shank and jaws and an upper portion engaging and supported by said projection and spaced above said jaws, and means for securing said parts in the shuttle.

2. In a loom shuttle, a pair of weft carrier holding spring jaws, a shank piece of soft steel welded between said jaws at one 55 end thereof and having a projection extend-

ing above the plane of said jaws, a U-shaped filler fitting and inclosing said projection on three sides thereof, and a guide plate 60 having a portion supporting said shank piece and jaws and having another portion supported by said projection and filler.

3. In a loom shuttle, a pair of weft carrier holding spring jaws, a shank piece to 65 which said jaws are welded, a guide plate having a portion overlying said shank piece, said shank piece having an upward projection engaging said guide plate, and a U-shaped filler inclosing said projection and 70 extending forwardly thereof, said filler forming a support for said guide plate supplemental to the projection on said shank piece and also providing additional bearing surface against the sides of the shuttle 75 recess.

4. In a loom shuttle, a pair of weft carrier holding spring jaws, a shank piece therefor having an upward projection above said springs, a guide plate having an upper portion 80 overlying said projection, and a U-shaped filler inclosing said projection and resting on said springs, said filler engaging and supporting said guide plate at two 85 different points and positioning the plate longitudinally of the shuttle.

5. In a loom shuttle, a pair of weft carrier holding spring jaws, a shank piece of soft steel welded between said jaws at one 90 end thereof and having a projection extending above the plane of said jaws, a U-shaped filler fitting and inclosing said projection on three sides thereof, and a guide plate having a portion supporting said shank piece and jaws and having another portion 95 supported by said projection and filler, said filler having a beveled extension engaging and supporting the inclined directing portion of said guide plate.

6. In a loom shuttle, a pair of weft carrier holding spring jaws, a shank piece therefor having an upward projection above said springs, a guide plate having an upper portion overlying said projection, and a 100 filler piece positioned and supported by 105 said projecting shank piece and engaging said springs on their upper edges, said filler piece also engaging and supporting said guide plate and positioning the same longitudinally of the shuttle.

In testimony whereof I have hereunto affixed my signature.

LOUIS E. CHASE.
